conductor 34 from square wave generator 26 is connected to the cathode 28. A suitable bias may be introduced, as is indicated by the battery 36. With this arrangement the electron stream will be intermittent, it flowing during the positive half and being interrupted during the negative half of the square wave. The resulting electron stream pulses are of proper frequency but of long duration. The use of a square wave is merely illustrative, other wave forms being suitable as described later.

Another part of the alternating current from source 24 is fed through a phase shifter 38 and thence to another square wave generator 40. The phase shifter 38 may simply reverse the phase of the alternating current, in which case a simple inverter may be used, and the square wave output from generator 40 will be 180° out of phase with the output from generator 26. If desired the square wave output of generator 40 may be rectified to leave only the positive halves of the cycle, its output being represented by Figure 6.

This output is fed to the collector plate 16. In the present case the output is applied across a resistor 42 connected in series with collector 16. A radio frequency choke 44 may be put in the circuit to confine the radio frequency or pulse energy to the output lead 46. It will be evident that the operation is properly synchronized, there being no collecting potential on collector 16 during the flow of the electron stream and its formation into a ring, and there being no electron stream other than the formed ring when the ring is being collected by the potential then applied to the collector 16. The instantaneous collection of the entire ring of electrons results in a single sharp pulse, marked 48 in Figure 7. The additional oscillations shown in Figure 7 take place when the pulse is fed to a radiator or other circuit tending to resonate. The pulse duration is so extremely short that in practice the spacing between pulses will ordinarily be much greater, relative to the duration of the pulse, than is shown in Figure 7.

Reverting now to Figure 8, the formation and collection of the electron ring preferably takes place within an electrostatically shielded space, provided in the present case by a cylindrical shield 48. The cylinder is made of a highly conductive metal and is preferably closed at the top and bottom, thereby providing a space which is shielded against electrostatic fields but not against the magnetic field. An opening 50 is provided in the side wall of the shield near one end, and the collector plate 16 is a disc disposed near the other end of the shield. The lead-in 52 of collector 16 is insulated from the shield by means of a glass bead 54. The shield 48 is supported by a lead-in 56 which also permits the application of a high positive potential to the shield (as is schematically indicated by the battery 58 in Figure 1. In practice all necessary potentials may be taken from a suitable power supply pack, rather than from batteries).

The electron gun 14 (Figure 8) may be disposed horizontally and aimed directly into the opening 50, but for reasons discussed later, I prefer to dispose the gun vertically and to deflect the electron stream from vertical to horizontal direction, as is indicated in Figure 8. The necessary deflection may be obtained by means of a curved deflecting plate 60 carried by a lead-in 62, to which a suitable negative potential may be applied. Figure 1 shows a battery 64 for this purpose.

If the electron gun were mounted horizontally at the side of the tube, the deflecting electrode with its attendant defocussing would be eliminated. However, in such case the gun design would be far more complicated, because the magnetic field would fringe over into the gun structure and would modify the motion of the electrons even while they were being accelerated. Moreover, the focussing action of the magnetic field which obtains when the electrons are projected along the lines of force would be lost.

The electron gun itself may be of conventional character (see Figure 8), it comprises the usual heating filament and leads, the usual concave cathode 28, and appropriate focussing electrodes 66 and 68, in addition to the intensity grid or control electrode 30. Appropriate lead-in wires are provided for each of the electrodes, and these act also as supports for the same. The generally concentric relation between the tube and the solenoid 18 surrounding the same is shown in Figures 2 and 3 of the drawing.

A tube of the type described will yield a large power output. Fairly heavy beam currents are obtainable from the electron gun. The operating voltages may be made very high because the tube is large enough to insure adequate insulation without introducing the transit time difficulties encountered in conventional ultra-high frequency circuits when dimensions are increased.

For a greater power output than that obtainable from a single tube, a plurality of pulser tubes of the type here described may be used. A number of tubes may be operated in parallel, such an arrangement being shown in Figure 9, in which each of the pulser tubes with associated circuits is indicated at 88, these being connected to a plurality of dipoles or other directive radiators 90 (only one of which is shown) by means of concentric or other suitable transmission lines 92. To ensure synchronization all of the units are preferably energized from a common alternating current source 24. All of the tubes may have common field coil excitation, and a common power supply circuit, including the square wave generators and phase shifter. In addition, fine adjustment phase changing means may be provided to synchronize the pulses despite variations in tube parameters. If desired, the transmission lines 92 may be made adjustable in length, thereby acting as the phase adjusting means for the various antennas.

A complete pulse echo system using the present invention is schematically illustrated in Figure 10. In this figure the alternator 24 corresponds to the source 24 in Figures 1 and 9. The transmitter 72 comprises pulser tubes with a control wave generator and a collector wave generator, all as was described in connection with Figures 1 and 9. The output of the transmitter is supplied directly to a suitable radiating system, schematically indicated at 74. While a single dipole is shown, it will be understood that a directive array of dipoles is ordinarily employed. The echo from the object intercepted by the transmitted radio energy is picked up by a directive receiving antenna or array 76. The echo energy is fed to a receiver 78, the output of which is applied to the deflecting electrodes of an oscilloscope 80. A sweep wave obtained from a sweep wave generator 84 is applied to the sweep electrodes of the oscilloscope 80. It will be noted that the sweep wave generator 84 is driven or synchronously controlled

by alternating energy from the primary source 24. It will be understood that more than one oscilloscope may be employed. For example, one oscilloscope may be used for azimuth tracking, another for elevation tracking, and still another for ranging, the first two having independent receiving arrays and receivers. If desired, two receiving antennas may be used for each receiver, these being either physically or electrically displaced at an angle relative to one another, and a suitable switching device used to periodically connect one and then the other antenna to the receiver. This provides a so-called "dual receiver" for so-called "double tracking." A wholly or partially blocking circuit 86 may be used to help protect the receiver from the transmitter during radiation of the pulse.

Inasmuch as the echo is substantially a radio frequency peak, rather than a detected modulation of a radio frequency carrier, the duration of the echo pulse is exceedingly short. This will produce a very narrow peak on the oscilloscope screen, and the trace may therefore be too faint at the peak. To merely increase the steady intensity of the electron beam is not desirable as it will help shorten the life of the cathode, and will help burn out the fluorescent coating of the oscilloscope screen. Furthermore, increasing the sweep frequency so as to allow the peak to receive a larger fraction of the total illumination per cycle is undesirable, for the sweep frequency is and should be synchronized with the pulse rate. In accordance with a further feature of the present invention, the trace is greatly intensified solely during reception of the echo peak.

An arrangement for this purpose is shown in Figure 11, in which the sweep electrodes are indicated at 100 while the deflecting electrodes are indicated at 102. The input signal from the receiver is applied to the deflecting electrodes 102 by means of conductors 104. The electron stream is emitted from cathode 106, and its intensity is controlled by an intensity grid 108. The beam is focused by appropriate focusing electrodes 110. The intensity grid 108 is biased by means of a resistor 112. This bias is selected to normally keep the cathode ray at a relatively low or normal intensity level. The circuit of the intensity grid 108 is also connected to the input conductors 104 from the receiver, as by means of blocking condenser 114 and wire 116. The echo peak when applied to the deflecting electrodes is a positive peak, and this positive peak when fed to the intensity grid 108 greatly magnifies the intensity of the cathode ray at the critical time when it must reproduce the peak. This feature is useful in any case where the signal to be pictured on the oscilloscope is of very short duration compared to the period of the sweep, and where for some reason it is undesirable to use a high sweep frequency. I use a large beam current momentarily, preferably with a persistent screen, in order to get adequate visibility for the trace.

Inasmuch as a high voltage is employed on the shielding and collecting electrodes, the tube may if desired be shielded against X-rays. This is illustrated in Figure 12, in which the tube 120 is enclosed within a lead casing 122.

Figure 12 also shows how the output of the tube may be connected to a concentric line. The concentric line comprises a center conductor 124 and an outer tube 126. This is preferably enlarged at 128 to enclose the lead sheath 122. The cathode is connected to the metal hous-

ing at 130. A lead ring 132 may be added around the end of the tube 126 to complete the X-ray shielding. The tube 126 and housing 128 are made of a highly conductive metal, such as copper. The housing 122, 128 is provided with additional passages and insulators (not shown) for the other conductors needed to energize and to bias the various electrodes in the tube. The bushings and insulators for this purpose are designed to withstand the necessary voltages, and are dimensioned to provide sufficient clearances to avoid corona discharge and the like.

As an aid in computing the proper tube dimensions and pulse frequency, I may point out that inasmuch as the electrons move in a plane perpendicular to the magnetic field and are in an electrically field-free region, they will move in a circular path. The time taken for the electron to make one circuit is given by the formula

$$T = \frac{2\pi}{He/m}$$

and the radius of the path is given by

$$r = \frac{p}{He}$$

in which T is the time in seconds, H is the magnetic field strength in Gauss, e/m is the ratio of the charge to the mass of an electron in emu per gram, r is the radius in centimeters, and p is the momentum of the electron in CGS units. The period of the control wave if it is square (reciprocal of the pulse frequency) should be less than or equal to but not greater than twice the time needed to form one complete ring of electrons. In other words, the time may be limited so that only a fraction of a ring is formed for each collection on the collector, or the time may be increased until a complete ring is formed, but any greater increase is undesirable because the resulting mutual repulsion of the electrons will spread the electrons, thus spoiling the desired instantaneous collection which is essential for the production of an exceedingly short pulse, and what is even more important, causing some of the electrons to be collected by the shielding electrode 48.

The collection time is a function of the collecting voltage, the distance between the plane of ring formation and the plane of collection, and the thickness of the electron beam. If the plane of the ring is not perpendicular to the magnetic field, the ring will stretch axially into a portion of a helix, and travel either toward the collector or away from it during the formation time. Such an effect will vitiate the operation. The extent of the harmfulness of this effect, in any particular case, is determined by the magnitude of the departure of the actual tube and beam geometry from the ideal. An additional electrode parallel to the collector and situated at the opposite end of the cylindrical shield will alleviate this condition. Ring "tilt" is then overcome by the provision of small suitable D.-C. potentials to the two plates during the time of ring formation. Alternative methods are to control the direction of the beam by varying the potential on the deflecting electrode, thereby to ensure the desired perpendicularity, or to provide a local distortion of the magnetic field in the region of ring formation. This last may be accomplished by putting additional turns on the solenoid in certain regions, or by external shimming of the field with rings of magnetic materials. The desired field distortion may be treated much

as is done with field distributions heretofore provided when fringing of a field was observed in focusing problems encountered in the operation of cyclotrons and induction accelerators. A third method is to replace the simple cylindrical shield by a more complicated one containing additional electrodes, barriers, projections, or extensions serving to give the desired electronic planar concentration. Any residual tilt will smear the pulse somewhat, the smear being broader the larger the radius of the electron ring.

With high collection voltages, small spacing, narrow beams and good geometry, pulses of duration measured in very small fractions of a microsecond may be obtained.

The use of a square control wave is not necessary. Departure from this wave form simply yields a distribution in velocity of the ring electrons, and thus a corresponding distribution in radii of curvature of the trajectories. The circle is replaced by a spiral. A sawtooth wave, with alternate teeth blocked out, may be used. For accelerating potentials high enough to make the kinetic energy of the electrons an appreciable fraction of the rest energy, e. g. of the order of 100 kv., a non-square wave will give a distribution in mass and thus a spread in collection time of the ring electrons. This relativistic pulse broadening is usually negligible at all practical voltages. If a gradually increasing or gradually decreasing voltage, for example, sawtooth, is employed, the period of formation may be lengthened relative to the pulse period (the time T) because one then obtains a multturn spiral rather than a ring. This gives a higher charge transport per pulse, and thus a larger power output. A disadvantage is that lengthening the ring-forming time and increasing the number of electrons aggravates the defocusing effects of the mutual repulsions of the electrons, and so broadens the pulse. However, multiple turns are possible with a spiral path, but should not be permitted at all with a circular path.

It may be desired to vary the pulse frequency in order to vary the maximum range of the pulse echo system. The time T is fixed by the field strength H, and the latter is preferably kept at a constant value because of the inconvenience of changing the field strength, with its concomitant change in radius of the electron ring. As indicated above, forming multturn spirals enables one to use a lower pulse frequency for a longer range without changing the field strength. The larger range is automatically accompanied by a larger power output, which is a desirable feature if the radio range is to keep up with the theoretically available echo-time range.

If a higher pulse frequency (for shorter range work) than $1/T$ is desired, say n/T where n is an integer, and a full electron ring rather than $1/n$ th of a ring is to be collected in order to maintain large power output, n tubes may be employed instead of one. These tubes are connected in parallel as in Figure 9, the only change being that each of the n tubes is made to differ from its neighbor in the phase of its A.-C. excitation by

$$\frac{2\pi}{n}$$

Each tube has its own control and collector wave generators. Those skilled in the art know how to obtain the desired phase splitting. As an alternative, an n -phase alternating current may

be used, each phase feeding its own pulser tube. For greater power, each of the n tubes may be replaced by a number of tubes in parallel, as described earlier in connection with Figure 9.

I prefer to dispense with sharp tuning in the receiver, and instead use an amplifier of the linear type used for counting single particles in nuclear physics. These amplifiers are of extremely high gain, can be stabilized, are of RC type, and have a finite time constant or resolving time, i. e. for incoming pulses closer together than a certain critical amount, the output is a single large pulse. The composite transmitted pulse should be completely keyed off in an interval smaller than the resolving time. This may be done by having sufficient dipole damping so that the oscillation amplitude drops to substantially zero during the resolving time interval. The resolving time can always be increased by adjusting the RC values in the receiver. The receiving dipoles are preferably similar to the transmitting dipoles, this providing sufficient receiver tuning for the present purpose.

The system has the advantage that the UHF is supplied without the use of resonant circuits or conventional oscillators with their accompanying design, adjustment and power output difficulties and limitations. The pulse is the equivalent of a band of frequencies clustered about a mean frequency given by $f=1/t$ where t is the duration of the pulse—consequently length and spacing of the dipoles are not as critical as is the case where a conventional oscillator is employed. Transmitter circuits are considerably simplified. The keyer is replaced by a control wave generator, and amplifiers, oscillators, limiters, pulse sharpeners, etc. are eliminated. A rather large power output per tube is obtained because distributed and tube capacitance, transit time, etc. do not limit the size of the tube. Also, with proper design, high voltages can be used and heavy beam currents are obtainable. Plate dissipation can be spread over a plate of large area, and lasts for a period of time much shorter than pulse durations currently employed, thus permitting higher power output per tube per pulse. No difficulties with respect to feed-back between output and input, parasitics, distributed capacitance and inductance of leads, etc., present themselves.

It is believed that the construction and operation of my improved pulser tube and pulse echo system, as well as the many advantages thereof, will be apparent from the foregoing detailed description. It will also be apparent that while I have shown and described my invention in several preferred forms, many changes and modifications may be made without departing from the spirit of the invention as sought to be defined in the following claims. In the claims the term "antenna" is intended to include other directive radiators such as an electromagnetic horn, as well as the use of reflectors, directors, lenses, etc., associated with radiating elements.

I claim:

1. In the operation of an electron tube comprising an electron source and an electron collector, the method of producing pulses which includes the steps of forming and storing a mobile charge distribution during a certain period of time, causing said charge distribution to remain juxtaposed to said collector at a fixed distance therefrom during said period of time, and then collecting said mobile charge distribution in a time shorter than the formation time by suddenly

creating an electrostatic field in the region between said charge distribution and said collector. 2. In the operation of an electron tube comprising an electron source and an electron collector, the method of generating extremely short pulses which includes subjecting the tube to a magnetic field, guiding a stream of electrons in a direction perpendicular to the magnetic field, whereby the stream curls in a plane spaced from the collector, and thereupon applying a positive potential to the collector.

3. In the operation of an electron tube comprising an electron gun and an electron collector plate all surrounded by a solenoid having its axis generally perpendicular to the plate, the method of generating extremely short pulses which includes shooting a stream of electrons in a direction perpendicular to the magnetic field of the solenoid, whereby the stream curls in a plane spaced from but generally parallel to the collector, and thereupon applying a positive potential to the collector so that all of the electrons are gathered almost simultaneously on the collector, and so provide a relatively powerful pulse of very short duration.

4. In the operation of an electron tube comprising an electron gun and an electron collector, the method of generating extremely short pulses which includes subjecting the tube to a magnetic field perpendicular to the collector, periodically shooting a stream of electrons in a direction perpendicular to the magnetic field, whereby each stream curls in a plane spaced from but generally parallel to the collector, and periodically applying a positive voltage to the collector, the latter voltage being applied in synchronism with the intermittent electron stream but out of phase therewith, all of the electrons of each stream being gathered almost simultaneously on the collector and thereby providing relatively powerful pulses of very short duration.

5. In the operation of an electron tube comprising an electron gun, a control grid, and an electron collector, the method of generating extremely short pulses which includes subjecting the tube to a magnetic field perpendicular to the collector, generating an alternating current having the desired pulse frequency, deriving a control wave from a portion of the alternating current, so applying the control wave to the control grid of the electron gun that intermittent long-duration pulses of electrons are discharged from the gun, guiding the electron streams in a direction generally perpendicular to the magnetic field at a point spaced from the collector, so that each electron stream curls in a plane spaced from but substantially parallel to the collector, substantially shifting the phase of another portion of the aforesaid alternating current, deriving a collector wave from the phase-shifted alternating current, and applying the collector wave to the collector.

6. In the operation of an electron tube comprising an electron gun, a control grid, and an electron collector all surrounded by a solenoid, the method of generating extremely short pulses which includes generating an alternating current having the desired pulse frequency, deriving a control wave from a portion of the alternating current, so applying the control wave to the control grid of the electron gun that intermittent long-duration pulses of electrons are discharged from the gun, guiding the electron streams in a direction generally perpendicular to the magnetic field at a point spaced from the collector, so that

each electron stream curls in a plane spaced from the collector, shifting the phase of another portion of the aforesaid alternating current by approximately 180°, deriving a collector wave from the phase-shifted alternating current wave, and applying the positive portion of the collector wave to the aforesaid collector, whereby all of the electrons of each of the relatively long electron stream pulses are gathered almost simultaneously on the collector to form relatively powerful and extremely short pulses.

7. A pulse generating tube comprising an electron source, a control electrode, a cylindrical electrostatic shield closed at both ends but having an opening in the side near one end, a collector within the shield near the opposite end, means to guide the electron stream from the source into the opening in a direction transverse to the sides of the shield, and magnetic means to provide a magnetic field in the shield extending in the direction of the sides of the shield.

8. A pulse generating tube comprising an electron source, a control electrode, a collector, magnetic means to provide a magnetic field, means to guide the electron stream from the source in a direction perpendicular to the field, means to periodically apply a potential to the control electrode in order to make the electron stream intermittent, means to periodically apply a positive potential to the collector in order to collect all of the electrons of each stream substantially instantaneously, the periodic potentials being synchronous but out of phase.

9. A pulse generating tube comprising an electron source, a control electrode for said source, a cylindrical electrostatic shield having an opening in the side near one end, a collector within the shield near the opposite end, means generating a magnetic field within the shield, means to guide the electron stream into the opening in a direction transverse to the magnetic field, means to periodically apply a potential to the control electrode in order to make the electron stream intermittent, and means to periodically apply a positive potential to the collector in order to collect all of the electrons of each stream substantially simultaneously, the periodic potentials being synchronous but out of phase.

10. A pulse generating tube comprising an electron gun, a control grid, a cylindrical electrostatic shield having an opening in the side of the cylinder near one end, a collector disc within the cylinder near the opposite end, means to guide the electron stream into the opening in a direction transverse to the axis of the cylinder, a magnet generating a field in the direction of the axis of the cylinder, means to apply a periodic potential to the control grid in order to make the electron stream intermittent, and means to apply a periodic positive potential to the collector in order to collect all of the electrons of each stream substantially instantaneously, the periodic potentials being synchronous but out of phase.

11. Pulse generating apparatus comprising an electron source, a control electrode, a collector plate, a magnet providing a magnetic field, means to guide the electron stream in a direction perpendicular to the said field, an alternating current generator having the desired pulse frequency, a control wave generator driven thereby, connections applying said control wave to the aforesaid control electrode, a phase shifter for a portion of the aforesaid alternating current, a collector wave generator driven by the phase-

11

shifted alternating current, and connections for applying the resulting collector potential to the collector.

12. Pulse generating apparatus comprising an electron source, a control grid for said source, a cylindrical electrostatic shield having an opening in the side near one end, a collector near the opposite end, means to provide a magnetic field in said shield, means to guide the electron stream into the opening in a direction perpendicular to the field, an alternating current generator having the desired pulse frequency, a control wave generator driven thereby, connections applying said control wave to the aforesaid control electrode, a phase shifter for a portion of the aforesaid alternating current, a collector wave generator driven by the phase-shifted alternating current, and connections for applying the resulting potential to the collector.

13. Pulse generating apparatus comprising an electron gun, a control grid, a cylindrical electrostatic shield having an opening in the side near one end, a collector disc near the opposite end, means to guide the electron stream into the opening in a direction parallel to the collecting disc, a solenoid surrounding the tube with its axis in the direction of the axis of the cylinder, an alternating current generator having the desired pulse frequency, a square wave generator driven thereby, connections applying said square wave to the aforesaid control grid, a phase reverser for a portion of the aforesaid alternating current, a square wave generator driven by the phase-reversed alternating current, and connections for applying the resulting potential to the collector, whereby the long pulses of electrons from the gun are instantaneously gathered by the collector to form relatively powerful short pulses.

14. A pulse echo system for locating and ranging, said system comprising a directive antenna, a pulse generator as defined in claim 11 connected to said antenna, at least one directive receiving antenna, a tracking oscilloscope energized from said receiving antenna, and a sweep wave generator for the oscilloscope, said sweep wave generator being driven by a portion of the alternating current referred to in claim 11, whereby all parts of the system are maintained in synchronism.

15. A pulse echo system for locating and ranging, said system comprising a directive antenna, a pulse generator as defined in claim 12 connected to said antenna, at least one directive receiving antenna, a tracking oscilloscope ener-

12

gized from said receiving antenna, and a sweep wave generator for the oscilloscope, said sweep wave generator being driven by a portion of the alternating current referred to in claim 12, whereby all parts of the system are maintained in synchronism.

16. A pulse echo system for locating and ranging, said system comprising a directive antenna, a pulse generator as defined in claim 11 connected to said antenna, at least one directive receiving antenna, a tracking oscilloscope having deflection electrodes energized from said receiving antenna, a sweep wave generator for the sweep electrodes of said oscilloscope, said sweep wave generator being synchronized by a portion of the alternating current referred to in claim 11, a control or intensity grid in said oscilloscope, and means so connecting the receiving antenna to said intensity grid as to increase the intensity of the trace during reception of the echo.

17. A pulse echo system for locating and ranging, said system comprising a directive antenna, an untuned pulse generator as defined in claim 11 connected to said antenna, at least one directive receiving antenna, and an untuned receiver connected to said antennas.

18. A pulse echo system for locating and ranging, said system comprising a directive antenna, an untuned pulse generator as defined in claim 11 connected to said antenna, at least one directive receiving antenna, and an untuned receiver connected to said antenna, a tracking oscilloscope energized from said untuned receiver, and a sweep wave generator for the oscilloscope, said sweep wave generator being driven by a portion of the alternating current referred to in claim 11 in order to maintain all parts of the system in synchronism.
